UNITED STATES PATENT OFFICE.

CHARLES F. LACOUR, OF GRASSY POINT, NEW YORK.

KILN-HEAD GUIDE.

SPECIFICATION forming part of Letters Patent No. 270,444, dated January 9, 1883.

Application filed July 31, 1882. (No model.)

To all whom it may concern:

Be it known that I, CHARLES F. LACOUR, of 5
Grassy Point, in the county of Rockland and
State of New York, have invented a new and
useful Improvement in Kiln-Head Guides, of
which the following is a full, clear, and exact
description.

Reference is to be had to the accompanying
drawings, forming part of this specification,
10 in which similar letters of reference indicate
corresponding parts in both the figures.

Figure 1 is a front elevation of my improve-
ment, illustrating its use. Fig. 2 is a sectional
elevation of the same, taken through the broken
15 line *xx*, Fig. 1.

The object of this invention is to facilitate
the setting of the green bricks in preparing
brick-kilns, and also to promote accuracy in
forming the heads of the kilns.

20 The invention consists in a kiln-head guide
constructed with a frame having a close panel
in its lower part and cross-slats in the middle
and upper parts, and provided at its upper
part with adjustable fastenings for connecting
25 it with a side prop of the kiln. The guide is
also provided with cords for giving a true taper
to the sides of the center arch, and with a
guide-cord for adjusting it in line with its for-
mer position, as will be hereinafter fully de-
30 scribed.

A represents one of the kiln-shed posts. B
are the side props, which are attached to the
posts A.

C is the frame of the guide, which is made
35 of a length equal to the height of the kiln-
heads, and of a width equal to the thickness
of an arch. The lower part of the guide, for
a height equal to the height of the fire-cham-
bers, is provided with a close panel, D. The
40 part of the guide above the panel D is pro-
vided with cross-slats E, attached at their ends
to the side bars of the guide and placed at a
distance apart equal to the height of two courses
of green bricks.

45 To the top bar of the guide-frame C, and to
a cross-bar at the upper edge of the close panel
D, are attached the ends of two cords, F, the
lower ends of which are placed at a distance
apart equal to the thickness of the lower part

of the center arch, and their upper ends are 50
placed at a distance apart equal to the thick-
ness of the upper part of the said center arch.
The cords F thus serve as guides in setting the
bricks of the center arch, so that the said arch
will have a uniform inclination upon both sides, 55
as shown in Fig. 1. In setting the bricks for
the other arches the cords F are not used.

G is a cord which passes through holes in
the lower ends of the side bars of the guide-
frame C, and is provided with pins H at its 60
ends to be driven into the ground. The cord
G may be attached to the posts A, and is in-
tended as a guide in adjusting the lower end
of the guide E D E for another arch, so that
the guide will be in line with its former posi- 65
tion and the head of the kiln will be true.

To the outer sides of the upper parts of the
side bars of the guide-frame C are attached
long keepers I, through which and into or
through the side bars of the frame C are formed
70 holes to receive the pins J, by which the shanks
of the hooks K are hinged to the said keepers
and side bars. The hooks K are designed to
be hooked upon the upper side prop, B, and
are made of such a length as will give the re- 75
quired inclination to the guide C D E, and con-
sequently to the head of the kiln, the holes in
the keepers I and in the side bars of the guide-
frame allowing the hooks K to be adjusted as
the height of the side prop, B, may require. 80

Having thus described my invention, what I
claim as new, and desire to secure by Letters
Patent, is—

1. A kiln-head guide constructed substan- 85
tially as herein shown and described, and con-
sisting of the frame C, having a closed panel,
D, in its lower part and cross-slats E in its
middle and upper part, as set forth.

2. In a kiln-head guide, the combination,
with the guide-frame C, of the long keepers I 90
and the hinged hooks K, substantially as here-
in shown and described, whereby the said
guide can be readily secured to the upper side
prop, as set forth.

3. In a kiln-head guide, the combination, 95
with the frame C and the cross-slats E, of the
cords F, arranged with their upper ends nearer
together than their lower ends, substantially

as herein shown and described, whereby a true taper can be given to the center arch, as set forth.

4. In a kiln-head guide, the combination, 5 with the perforated lower ends of the side bars of the frame C, of the cord G, substantially as herein shown and described, whereby the

guide, when adjusted, can be kept in line with its former position and the head of the kiln kept true, as set forth.

CHARLES F. LACOUR.
